UNITED STATES PATENT OFFICE.

SILVIUS J. MORRISON, OF CHICO, CALIFORNIA.

APPARATUS FOR WIRING FRAMES.

1,407,435.

Specification of Letters Patent. Patented Feb. 21, 1922.

Application filed June 1, 1921. Serial No. 474,230.

To all whom it may concern:

Be it known that I, SILVIUS J. MORRISON, a citizen of the United States, residing at Chico, in the county of Butte and State 5 of California, have invented certain new and useful Improvements in Apparatus for Wiring Frames, of which the following is a specification, reference being had to the accompanying drawings.

10 This invention relates to an apparatus for wiring frames and has relation more particularly to a device of this general character especially designed and adapted for use in the wiring of frames such as used in bee culture, and it is an object of the invention to provide a device of this character having novel and improved means whereby the frame is effectively held in desired position during a wiring operation.

20 It is also an object of the invention to provide a novel and improved apparatus of this general character including means whereby a spool, or the like, of wire may be held under tension and in a position to facilitate the wiring operation.

25 Another object of the invention is to provide a device of this general character having novel and improved means whereby the frame is maintained in desired position during a wiring operation together with means for ejecting or throwing out the frame.

30 The invention consists in the details of construction and in the combination and arrangement of the several parts of my improved apparatus for wiring frames whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:

45 Figure 1 is a view in perspective illustrating an apparatus constructed in accordance with an embodiment of my invention, a frame in applied position, and

50 Figure 2 is a transverse sectional view taken through the devices illustrated in Figure 1, certain of the parts being in elevation.

As disclosed in the accompanying draw-

ings, B denotes a base preferably oblong in 55 form and of desired dimensions, and which has disposed transversely of its under surface the cleats 1 which provide a support for the base B. The upper or working surface of the base B along one longitudinal 60 marginal portion thereof has bolted, as at 2, or otherwise secured thereto a strip 3, said strip extending from one end of the base B to a predetermined point inwardly of the opposite end of the base. The intermediate portion of the strip 3 is reduced in width, said reduced portion providing an elongated recess 4 extending along the major portion of the strip 3. This recess 4 is adapted to snugly receive the top bar 5 of the 70 frame F, said frame being of a type employed in connection with bee hives.

Bolted or otherwise secured, as at 6, to the opposite longitudinal marginal portion of the base B is a strip 7, and secured to 75 the opposite end portions of said strip 7 and extending inwardly therefrom are the bolts 8, the heads 9 of said bolts being arranged inwardly of the strip 7. The bolts 8 are loosely disposed through the opposite 80 end portions of a strip 10 resting upon the base B and having movement relative to the strip 7. Interposed between the strips 7 and 10 are the expansible members 11, herein disclosed as coil springs encircling the bolts 8, and which expansible members operate to 85 constantly urge the strip 10 toward the heads 9 of the bolts 8. The intermediate portion of the strip 10 is also reduced in width to provide an inwardly facing recess 12 of a length to snugly receive the second or lower bar 14 of the frame F.

90 By having the strip 10 supported for yielding movement with respect to the strip 7, the frame F may be readily and conveniently applied in desired position upon the base B and held in such position during a wiring operation.

95 The base B, at a point in close proximity to the central part of the recess 4 in the strip 3, has provided there through a slot or opening 15, through which is adapted to pass from below an upstanding finger or arm 16 carried by an end portion of a lever 17. The lever 17 is arranged below the base B and extends transversely thereof and beyond the longitudinal marginal portion of the base B to which the strip 7 is secured.

100 At a predetermined point intermediate its

ends the lever 17 is operatively engaged with a bar 18 supported by and bridging the space between the cleats 1 whereby the lever 18 is capable of swinging movement in a vertical direction. Secured to the under face of the base B is a spring 19 which contacts with the lever 17 at the side of the bar 18 toward the strip 3 and whereby the lever 17 is normally maintained in a position whereby the finger or arm 16 is depressed below the upper surface of the base B. When it is desired to remove an applied frame F, the extended end portion of the lever 17 is depressed by hand, or if preferred, by a suitably connected pedal. This movement will result in an upward movement of the finger or arm 16 and in requisite contact with the top bar 5 to throw out or eject the applied frame F.

Bolted or otherwise secured, as at 20, to the upper face of the base B adjacent an end of the strip 3, is a block 21 provided with an upstanding spindle 22 on which is adapted to be mounted a spool 23 having wound thereon the wire W. Extending upwardly from the base B in close proximity to the block 21 and the adjacent end portion of the strip 3 is a staple or guide member 24 through which the wire is adapted to be threaded. At a point adjacent the staple or guide member 24 is an upstanding pin 25 around which the wire W is adapted to be hitched or wrapped for a purpose to be hereinafter more particularly referred to.

Secured to a marginal portion of the block 21 is an upstanding spring 26 which bears against the upper portion of the spool 23, said spring constituting a tensioning device for retarding the rotation of the spool and for imposing tension on the wire W drawn therefrom.

After the spool 23 has been mounted on the spindle 22, said spool, is held against displacement by threading a nut 27 upon the upper portion of the spindle 22 above the applied spool 23.

In practice, small nails 28 are driven in the opposite extremities of an end bar 29 of the applied frame F adjacent the spool 23 and which nails can be applied, if preferred, after the frame F has been arranged in working position. The operator, after passing the wire W through the staple or guide member 23, properly threads the wire 55 through the openings 30 in the end members 29 of the frame F and anchors the free end portion of the wire to the end member 29 of the frame adjacent the spool 23 by driving home the nail 28 remote from the spool 23.

If, during the threading of the wire, it is necessary to unwind additional wire from the spool 23, the operator takes hold of the central portion of the strand within the 65 frame adjacent the top bar 5 and pulls said

central portion inwardly of the frame or toward the bottom bar 12. This operation will pull the wire from the spool 23 and the wire will not kink due to the retardation afforded by the tensioning device or 70 spring 26.

After the wire W has had its free extremity anchored by the nail 28, as just referred to, the wire is wrapped or otherwise secured to the pin 25. The lever 17 is then operated to throw out or eject the frame F, and the central portion of the top bar 5 is grasped with the left hand and with a steady pull on the pin 25, all of the strands within the frame F are tightened and such 80 tightening of the strands within the frame is further facilitated by the operator pressing with his right hand the second strand of wire from the top bar 5 toward such top bar, said strands being preferably tightened 85 to the extent which will result in the strands singing. After the strands within the frame have been tightened as desired, a second nail is then tapped home with a suitable implement and after which the wire is cut and the 90 apparatus is ready for use in the wiring of the next frame.

It has been fully demonstrated in practice that with my improved apparatus, a frame can be wired in substantially one-half 95 minute and with an easy operation without kinks in the wire and also without injury to the hands of the operator.

From the foregoing description it is thought to be obvious that an apparatus for 100 wiring frames constructed in accordance with my invention is particularly well adapted for use by reason of the convenience and facility with which it may be assembled and operated, and it will also be obvious that 105 my invention is susceptible of some change and modification without departing from the principles and spirit thereof and for this reason I do not wish to be understood as limiting myself to the precise arrangement 110 and formation of the several parts herein shown in carrying out my invention in practice except as hereinafter claimed.

I claim:

1. An apparatus for wiring frames comprising, in combination, a frame holding means, a spool mounting positioned adjacent said means and means for ejecting a frame from the frame holding means. 115

2. An apparatus for wiring frames comprising a base, a frame holding means positioned thereon, and an ejecting means for the frame carried by the base. 120

3. An apparatus of the class described comprising a base, a frame holding means 125 positioned thereon, said base being provided with an opening, a lever positioned below the base and provided with an upstanding finger movable through the opening of the base to eject the frame. 130

4. An apparatus of the class described comprising a base, a frame holding means positioned thereon, said base being provided with an opening, a lever positioned below the base and provided with an upstanding finger movable through the opening of the base to eject the frame, and means for normally maintaining the finger in an inoperative position.
- 10 5. An apparatus for wiring frames comprising a base, a frame holding means mounted thereon, a holding pin carried by the base adjacent the frame holding means, and a supply of wire carried by the base and positioned adjacent the holding pin, the portion of the wire between the frame and sup-
- ply being adapted to be engaged with the pin.
6. An apparatus for wiring frames comprising a base, elongated strips mounted upon the base and arranged substantially in parallelism, one of said strips being movable relative to the other, and means for constantly urging said movable strip toward the second strip, the opposed faces of the strips being recessed to receive the adjacent portions of a frame interposed between the strips.

In testimony whereof I hereunto affix my signature.

SILVIUS J. MORRISON.
